INTERNAL-COMBUSTION ENGINE

Orville Z. Frazier, Elkhart, Ind., assignor of one-half to Harold Andresen, Elkhart, Ind.

Application September 15, 1945, Serial No. 616,603.

2 Claims. (Cl. 123—73)

1

This invention relates to internal combustion engines and particularly engines commonly known as "two cycle," in which each revolution entails a power stroke.

An object of the invention is to equip a two cycle engine with an improved type of cup-shaped piston, so formed with an intake port as to minimize fuel loss through exhaust ports and contamination of incoming fuel by combustion products.

Another object is to provide an improved drive connection from the piston to the shaft of an internal combustion engine, involving a manufacturing economy as compared to present practice.

Another object is to regulate fuel admission to the crankcase of a two cycle engine by a novel valve mechanism, affording an accurate and efficient control of the intake period in a relatively inexpensive manner, and assuring an adequate crankcase supply of carbureted air.

Another object is to provide an improved engine particularly adapted to be built in small sizes as power units for model aeroplanes and the like.

These and various other objects are attained by the construction hereinafter described and illustrated in the accompanying drawings, wherein:

Fig. 1 is a sectional elevation of my improved engine, the plane of section including both the shaft and cylinder axes.

Fig. 2 is a sectional elevation taken on the line 2—2 of Fig. 1.

Fig. 3 is a side elevational view of the engine, partially in section on the line 3—3 of Fig. 1.

Fig. 4 is a sectional detail taken on the line 4—4 of Fig. 2.

Fig. 5 is a sectional view of my engine as modified by the use of twin cylinders, the plane of section including the cylinder and shaft axes.

Fig. 6 is a relatively transverse section taken on the line 6—6 of Fig. 5.

Fig. 7 is a cross-sectional view taken on the line 7—7 of Fig. 6.

Describing first the construction as shown in Figs. 1—4, the reference character 1 designates a crankcase of approximate rectangular shape, and formed with circular openings 2 in its side walls 2a. Cover plates 3 and 3a for the openings 2 are secured by bolts 3b to the walls 2a and are cupped to extend through said openings into the crankcase to reduce its volume. Bearings 4a and 4b for a shaft 4 are centrally formed on the plates 3 and 3a, as outward projections there-

from. Between the cover plates, a pair of duplicate valve disks 5 are slidably splined on the shaft, respectively in sealing contact with the respective cover plates, and each disk is formed adjacent to its periphery with an arcuate slot 5b, serving as a fuel intake port. Said slots are centered at the shaft axis and in mutual registration parallel to such axis. A carburetor 6, of a highly simplified type as illustrated, is arranged to deliver fuel to a passage 7 underlying the crankcase and having two upwardly directed outlets 8 so spaced and formed as to deliver fuel through the walls 3 at opposed points thereof near the crankcase bottom, and against the disks 5 in the rotary paths of the slots 5b.

Between the disks 5 there are fixed on the shaft 4 a ring type eccentric 9 as a driving element for the shaft and a circular weight 10 for counter-balancing the eccentric, the weight having an eccentricity to the shaft opposed to that of the eccentric. Preferably said eccentric and weight are laterally abutting and have openings 11 continuously extending through both thereof in proximity to the shaft for receiving small coiled springs 11a which are compressed between and impose a sealing pressure on the slidable disks 5. The eccentric 9 fits within an opening 12 of a yoke 13, said yoke and opening being elongated transversely to the shaft adequately to afford the eccentric its shaft-driving rotation. To apply such rotation, the yoke must reciprocate up and down (transversely to its elongation) and is guided in such reciprocation by engagement of its ends with opposed parallel walls 14 of the crankcase.

For reciprocating the yoke, it is rigidly connected by a plate 15 to a piston 16 sliding in a cylinder 17 surmounting the crankcase and rigidly attached to the latter by bolts 18. The plate 15 and yoke preferably have substantially the same thickness as the eccentric, so that they may fit as does the eccentric between the weight 10 and one of the valve disks. The piston 16, differentiating sharply from common practice, has its skirt extending toward the headed outer end of the cylinder, and the cylinder head 19, which is held in place by the bolts 18, has a considerable inward extension 20 adapted to enter the piston with a minimum lateral clearance when the piston is in its outermost position (not shown). In arriving at its illustrated innermost position the piston uncovers one or more exhaust ports 21 in the cylinder wall, and one or more intake ports 22 in the inner end portion 55 of the piston are also uncovered. In all other

positions of the piston, it closes the exhaust ports and its intake ports are closed by the cylinder. The inward extension 20 of the cylinder head is preferably of a cup shape adapting it to house a spark plug 23.

In operation of the described engine, the arcuate ports 5b register with the two fuel delivery passages 8 just after commencement of the piston upstroke and maintain such registration during the major portion of such upstroke. Thus carbureted air enters the crankcase throughout the major portion of the upstroke responsive to the resultant pressure drop. At the same time a charge of fuel, previously drawn into the cylinder through the piston ports, is being compressed and such compressed charge is ignited by the spark plug when the piston is in a substantially raised position. As the piston completes its resultant downward power stroke, it uncovers the exhaust and promptly thereafter uncovers the intake ports of the piston. The illustrated arrangement of the intake and exhaust ports spaces them apart considerably more than has been the prior practice in two cycle engines, thereby affording spent gases a better chance of escape without contaminating incoming fuel. Also location of the intake ports near the bottom of the cup shaped piston permits incoming fuel to accumulate upwardly from said bottom displacing the exhaust gases toward the exhaust ports. Thus fuel loss through exhaust ports is materially reduced as compared to present practice and fuel contamination is materially reduced.

Driving the shaft from the piston through the yoke 13 and eccentric 9 derives various advantages, as compared to the common drive established by a crank or crank disk. As is well known, the common connecting rod drive exerts a considerable lateral thrust on a piston in the plane of connecting rod oscillation, such thrust being commonly designated "side slap." The tendency toward "side slap" is rendered much less through the type of drive illustrated and any such tendency is overcome completely by utilizing the yoke as a crosshead guided by the walls 14 of the crankcase.

A further advantage of the yoke and eccentric drive is that it lends itself to a compact installation of the valve disks 5 which effect accurate metering and timing of fuel delivery to the crankcase.

In eliminating connecting rods the described drive secures another important advantage. It is well known that the wear and breakage of connecting rods is a frequent source of trouble in crank-driven internal combustion engines. The surface distribution of wear in the described engine obviously greatly exceeds that in a crank type engine and the yoke and eccentric may easily be designed of strength adequate to resist the maximum stresses imposed in their use.

The construction shown in Figs. 5 and 6 satisfies the description of Figs. 1 and 2 except that the crankcase carries two substantially opposed cylinders 17', in each of which a piston 16' reciprocates, each piston being rigidly connected by a plate 15' to a yoke 13'. The counterweight 10 is eliminated, being replaced by one of two eccentric 9', these projecting in opposite directions from the shaft 4'. Preferably the two cylinders

have their axes spaced slightly lengthwise of the shaft to compensate for necessity of disposing the plates 15' and yokes in a side-by-side relation.

5 The twin cylinder construction affords double the power of the first-described engine with a relatively small increase of weight and size. While twin cylinder engines are not broadly novel, so compact and light an engine as is now disclosed is believed novel.

What I claim is:

1. An internal combustion engine comprising a casing, a shaft journaled in said casing, a cylinder fixed on the casing, a piston reciprocatory in the cylinder to and from the shaft, a drive connection from the piston to the shaft, said casing being formed with opposed parallel walls and opposed fuel inlets in such walls, a pair of valve members each of substantially a disk form, 15 rotative within the shaft and respectively engaging the respective parallel walls, said valve members being each formed with an elongated port curved in an arc centered at the shaft axis, said ports being registrable with said fuel inlets during a predetermined fraction of each revolution of the shaft, said engine including a provision for delivering fuel from the casing to the cylinder when the piston is in its approximate limiting position toward the shaft, and a spring compressed between and maintaining sealing engagement of the paired valve members with said parallel walls.

2. An internal combustion engine comprising a casing, a shaft journaled in said casing, a cylinder 35 fixed on the casing, a piston reciprocatory in the cylinder to and from the shaft, said casing being formed with opposed parallel walls and fuel inlets in such walls, a pair of valve members, each of substantially a disk form rotative with said shaft and respectively engaging the respective parallel walls, said valve members having fuel ports registrable with said fuel inlets during a predetermined fraction of each revolution of the shaft, a drive connection from the piston to the 40 shaft including an element fixed on the shaft between said valve members, and a spring mounted in said element and reacting between the valve members to maintain their sealing engagement with said parallel walls.
